(57) **CLAIM**

The ornamental design for a sanitary article for shopping cart handles, as shown and described.

DESCRIPTION

FIG. 1 is a front elevational view of a sanitary article for shopping cart handles showing our new design;

FIG. 2 is a rear elevational plan view thereof;

FIG. 3 is a top plan view thereof;

FIG. 4 is a bottom plan view thereof;

FIG. 5 is a side elevational view thereof; and,

FIG. 6 is a perspective view thereof.

The indicia and broken lines shown in the figures are for illustrative purposes only and are hereby disclaimed as forming no part of applicant's claimed invention.
